UNITED STATES PATENT OFFICE.

CONRAD SEIMEL, OF GREEN POINT, NEW YORK, ASSIGNOR TO CHARLES PRATT, OF NEW YORK CITY.

IMPROVEMENT IN SHEET-METAL CANS.

Specification forming part of Letters Patent No. **81,692**, dated September 1, 1868.

To all whom it may concern:

Be it known that I, CONRAD SEIMEL, of Green Point, in the county of Kings and State of New York, have invented a new and useful Improvement in the Construction of Sheet-Metal Cans; and I do hereby declare that the following is a full, clear, and exact description thereof, which will enable those skilled in the art to make and use the same, reference being had to the accompanying drawings, forming part of this specification.

The invention relates to a new and useful improvement in the construction of sheet-metal cans.

The invention consists in a novel manner of forming or constructing the body of the can, as will be hereinafter more fully described.

In the accompanying sheet of drawings, Figure 1 is a transverse section of the body of a sheet-metal can constructed according to my invention. *x x*, Fig. 2, shows the line of section; Fig. 2, a side view of the same.

Similar letters of reference indicate corresponding parts.

The body of the can is composed of two pieces of metal, *A A*, bent each in form so as to have the sides *a a* at right angles with each other, the metal at the angle of the sides *a a* being swaged or rolled so as to form a projection, *b*, of semi-cylindrical form, which extends the whole length of the piece of metal. The ends of each piece of metal *A* are also swaged or rolled to form a projection, *c*, similar to *b*.

The pieces of metal *B* are fitted together so that the projections *c* of one piece of metal *A* may lap within or over the projections *c* of the other piece *A*, the two pieces *A A* forming a square body. When the two parts or pieces *A A* are thus fitted together, the lapped projections *c* are dipped in molten solder, and said projections soldered together, so as to form a tight joint. The peculiarity of this joint consists of the curved projections *c*, which, in expanding under the heat of the molten solder, will not open or spread apart, but will remain in a sufficiently close state to form a tight joint when the solder becomes cool.

The curved projections *c* and *b* also stiffen the body of the can, and render it strong and durable.

I claim as new and desire to secure by Letters Patent—

The square or rectangular sheet-metal can, constructed, as described, of the two pieces *A A*, bent to have the sides *a a* at right angles to each other, and having formed at the angles the semi-cylindrical projections *b*, the ends of said parts *a a* being rolled to form projections *c*, lapping within and over each other, as herein described, for the purpose specified.

CONRAD SEIMEL.
